UNITED STATES PATENT OFFICE.

HUGO FLÜGGE, OF FLOERSGEHOFEN, GERMANY.

COOLING APPARATUS FOR LIQUIDS.

SPECIFICATION forming part of Letters Patent No. 739,595, dated September 22, 1903.

Application filed November 13, 1902. Serial No. 131,144. (No model.)

To all whom it may concern:

Be it known that I, HUGO FLÜGGE, inn-keeper, a subject of the King of Prussia, German Emperor, residing at Floersgehofen, near Erfurt, in the Kingdom of Prussia, German Empire, have invented certain new and useful Improvements in Cooling Apparatus for Liquids, of which the following is a specification.

My invention relates to cooling apparatus for liquids; and the object of my invention is to provide an apparatus by means of which the carbonic-acid gas used in an apparatus for supplying beer or other similar liquids under gaseous pressure can at the same time be also used for the purpose of cooling the liquid to be served out, this device therefore doing away with the necessity of cooling the liquid by means of ice, as hitherto was usually the case.

The principal feature of my cooling apparatus is the arrangement of a spiral pipe, which is securely fixed within a chamber containing water or other similar fluid. The carbonic-acid gas which flows through this spiral pipe cools the water surrounding the pipe to such an extent that it begins to freeze. Consequently the liquid to be served out, which is contained in air-tight glass cylinders and which are surrounded by the freezing water, can be cooled in this manner to any required degree.

One of the various forms in which my apparatus can be carried out is shown in the drawings accompanying this description.

Figure 1 shows a vertical cross-section on the line A B, Fig. 3. Fig. 2 shows a vertical cross-section on the line C D, Fig. 3. Fig. 3 shows a horizontal section on the line E F, Fig. 1. Fig. 4 is a plan view, and Fig. 5 is a front elevation of Fig. 1. The apparatus as shown in Figs. 1 to 5 of the drawings is only intended for one kind of liquid. On the other hand, the apparatus as shown in Figs. 6 to 8 can be used to cool simultaneously two different kinds of liquid—for instance, two different kinds of beer. Fig. 6 shows a vertical cross-section on the line G H, Fig. 7. Fig. 7 shows a horizontal section on the line J K, Fig. 6. Fig. 8 is a plan view of Fig. 6. Fig.

9 is a diagrammatic view of the whole apparatus.

The cooling apparatus 1 (shown in Figs. 1 to 5 of the drawings) consists of two cylindrical air-tight closed vessels 2 and 3 of glass, porcelain, stoneware, or any other similar material, which are arranged one within the other. These vessels are hermetically closed at the top and bottom by means of two plates 4 and 5.

The top plate 4 is provided with a dome-shaped cover 6, which may be made so as to unscrew. The places where the top and bottom plates 4 and 5 join the cylindrical vessels 2 and 3 are made to fit as tightly as possible by means of rubber packing 7. The top and bottom plates 4 and 5, as well as the dome-shaped cover 6, are secured as tightly as possible to the cylindrical vessels 2 and 3 by means of bolts 8. A spiral pipe α is arranged in the cylindrical vessel 2, which is filled with pure water. The place where the spiral pipe α passes through the top plate 4 and enters the cylindrical vessel 2 is also made to fit as tightly as possible by means of packing. The spiral pipe α is bent back at its lower end and passes upward through the center. The inlet end 9 of the spiral pipe α , which is closed by means of a stop-cock 10, as well as the outlet end 11, extends beyond the plate 4 into the dome-shaped cover 6. The cooling-chamber 13 is filled with water by means of a funnel 12 and can be emptied at any time by means of an outlet-valve 14.

When it is intended to use the apparatus 1, the cock 10 is opened and carbonic-acid gas flows from the carbonic-acid-gas reservoir 15 into the spiral pipe α . The gas passes through the pipe and then flows into another pipe 16 by way of the outlet end 11. (See Fig. 9.) The pipe 16, if desired, can be arranged in such a manner as to pass through a box-shaped receptacle 17, in which are kept bottles that are required to cool. Said pipe 16 is connected with a carbonic-acid-gas storage tank 18, which is in turn connected with the beer-barrel 22, from which the beer is forced by gas-pressure to the cooling apparatus 1. The carbonic-acid gas which passes through the spiral pipe α causes a very con-

siderable cooling of the water surrounding it. If the carbonic-acid gas is allowed to circulate through the spiral pipe for any length of time, ice will be found to have attached itself 5 to the spiral pipe α .

If it is desired to fill the chamber 19 between the cylindrical vessels 2 and 3 with beer, wine, or any other similar liquid, it is only necessary to open the valve 20, (see Fig. 10 9,) when the carbonic-acid gas will pass through the pipe 21 and enter the vessel 22, containing the said beer, wine, or other liquid as soon as the valve 23 has been opened and cause the liquid by its pressure to flow into 15 the chamber 19 by way of the pipe 24.

The pipe 24, which passes through the bottom plate 5 of the cooling apparatus 1, is bent round as soon as it has passed through the plate 5 and extends for a short distance in a 20 horizontal direction. This horizontally-arranged end 25 of the pipe 24 causes the liquid through which it enters the chamber 19 to do so with a rotating circling motion. It is due to this motion that the liquid does not 25 commence to freeze and that the carbonic-acid gas with which the liquid is impregnated does not escape. To enable the air to escape automatically from the cooling-chamber 19 as soon as the liquid to be cooled begins to 30 flow into the chamber, the top plate 4 is provided with a cock, or better still with a floating valve 26, which closes as soon as the liquid reaches it. An outlet-pipe 27, with a 35 cock 28, passes through the dome-shaped cover 6 and the top plate 4 into the cooling-chamber 19.

For the purpose of observing and being able to regulate at any time the temperature of the liquid to be cooled before it is served 40 a thermometer 29 is arranged within the cooling-chamber 19. If the cylindrical vessels 2 and 3 are made of glass, the thermometer 29 can be seen from the outside. If, on the other hand, the material of which the cylindrical vessels are made is of porcelain, stone-ware, or any other non-transparent material, 45 a glass inset or window must be arranged in the wall of the cylindrical vessel at some suitable place, by means of which the temperature 50 can be taken.

The cooling apparatus 1^a, as shown in Figs. 6 to 8 of the drawings, which, as already stated, is intended for two different kinds of liquids, is provided with two outlet-pipes. It 55 consists of five cylindrical vessels 30, 31, 32,

33, and 34, arranged one within the other, which are hermetically closed at each end by a top and bottom plate 4 and 5. The top plate 4 is provided with a dome-shaped cover 6. All parts are securely connected together 60 by means of bolts 8.

The spiral pipe α , with the stop-cock 10, is arranged in a similar manner to the one described in the apparatus shown by Figs. 1 to 5 of the drawings, but with this difference 65 that the water-chamber 13, within which the spiral pipe α is arranged, acts as a cooling-chamber in two opposite directions—that is to say, it brings about the lowering of the temperature in the two cooling-chambers 36 70 and 37, which are separated by it from each other and which serve for the cooling of the two different kinds of liquids.

The cylinders 30 and 31 are separated by an air-space 35, which serves the purpose of 75 preventing the inside cylinders being affected by the temperature of the outside air.

The apparatus as shown in Figs. 6 to 8 differs further from that shown in Figs. 1 to 5 in the shape of the spiral pipe α . The latter in this instance is not bent back at the bottom end and carried again upward, but runs straight on toward the bottom plate 5, through which it passes with two outlet ends; but this variation is of no importance. The 85 only purpose of the dome-shaped cover 6 is to improve the appearance of the apparatus.

Having now particularly described and ascertained the nature of my said invention and in what manner the same is to be performed, I declare that what I claim is—

In an apparatus for cooling beer, wine and the like, a cooling vessel having a coiled pipe arranged therein and connected with a source of gas-supply under pressure, a gas-storage 95 tank connected with said coiled pipe, a cask for containing the liquor to be cooled, a pipe connecting said cask with the gas-storage tank, a pipe connecting said cask with the cooling vessel, and an outlet from said cooling vessel for withdrawing the cooled liquor therefrom.

In testimony whereof I have hereunto set my hand in presence of two subscribing witnesses.

HUGO FLÜGGE.
